VIBRATOR FOR DENTAL USE

John E. Shultz, Pella, Iowa

Application September 24, 1935, Serial No. 41,932

1 Claim. (Cl. 248—121)

My invention relates to a vibrator intended for use by dentists in making plaster solutions, casts and the like.

It is the purpose of my invention to provide a very simple and inexpensive vibrator, which can be used in connection with a motor found in every dentist's office for vibrating material for making casts.

A further purpose is to provide such a vibrator having a base portion on part of which a motor may be placed for steadyng the vibrator and holding it in position, and having also an upright member to which is hinged a shelf, yieldingly held in position to be vibrated.

More particularly, it is my purpose to provide such a vibrator, comprised of a single piece of sheet metal, with parts bent in opposite directions to form a base, on part of which a motor may be supported, and having an upright portion provided with a recess through which a vibrator supported by the motor may extend, and having a shelf hinged above said recess on the opposite side of the upright portion from the base, which supports the motor, and provided with a spring, by which the shelf may be yieldingly held in substantially horizontal position.

Another object is to provide in such an upright portion a recess to receive the spring, when the shelf is folded up to position parallel with the upper part of the upright, and to provide a latch for holding the shelf in its folded position.

With these and other objects in view, my invention consists in the construction, arrangement and combination of the various parts of my vibrator for dental use, whereby the objects contemplated are attained, as hereinafter more fully set forth, pointed out in my claim, and illustrated in the accompanying drawing, in which:

Figure 1 is a perspective view of a vibrator embodying my invention.

Figure 2 is a side elevation of the same with the motor resting thereon, part of the shelf being shown in section.

Figure 3 is an end elevation of the rotary vibratory device on the motor; and

Figure 4 is a perspective view illustrating the shelf in raised folded position and held therein by the latch.

My vibrator may be made in various forms and of different materials, but for cheapness and simplicity, I have built it of sheet metal.

A single sheet forms the upright member 10, at the bottom of which a portion 11 is bent to horizontal position in one direction, and portions 12

and 13 are bent to horizontal positions in another direction.

It will be seen that the portions 12 and 13 may support a motor 14 by which the vibrator can be held in place and which provides the means for vibration.

The upright 10 is formed with a recess 15. A shelf 16 is hinged to the upright above the recess 15. An expansible spring 17 is fastened to the shelf 16 and to the upright 10 at a point above 10 the hinge line of the shelf.

The shelf is arranged to swing or fold from substantially horizontal position as shown in Figure 1, where it serves to support a receptacle for vibrating the contents thereof upwardly to position against and parallel with the upper part of the upright 10 as shown in Figure 4. When the shelf is so folded upwardly, the device may be stored on a shelf, and other articles can be placed on the members 11, 12, and 13, and the 20 vibrator will occupy a minimum amount of room.

The upright member 10 is provided with a recess or hole 18 above the hinge line of the shelf to receive the spring 17, as shown by dotted lines in Figure 2, when the shelf is folded up.

A swinging latch 19 is pivoted to the upright member 10 and may be swung to position for holding the shelf 16 up as illustrated in Figure 4.

On the under side of the shelf 16, I preferably fasten a sheet of rubber or the like 20 as a noise 30 deadening member.

The motor 14 is provided with a spindle 21 adapted to be mounted on the motor shaft 22 and provided with an eccentric disc 23 made of wood or any suitable material.

When in use, the shelf 16 is lowered to substantially horizontal position. The vibrating wheel is installed on the motor and the motor is set on the base members 12 and 13. This helps to hold the vibrator properly in place and also 40 makes it easy to adjust the motor to proper position for functioning.

The spindle 21 is extended through the recess 15 until the disc 23 is underneath the rubber sheet 20 on the bottom of the shelf 16. Then a 45 rubber cup or the like 24, containing the solution of water and plaster of Paris for example can be placed on the shelf 16 and held in position by hand.

The motor can be operated for vibrating the shelf. The spring is preferably so tensioned that it will normally hold the shelf slightly above the disc 23. Then when the dentist or his assistant puts the cup 24 on the shelf and presses down 55

slightly, he can bring it into operative relation to the disc 23.

The dentist then has one free hand for stirring the mixture or for adding to the ingredients 5 thereof.

Similarly this vibrator can be used for pouring casts or for pouring plaster solution into molds.

The purpose of vibration, of course, is to eliminate air from the plaster of Paris solution or 10 the casts, for thus getting a production of uniform density.

When the vibrator is not in use, the motor can be removed and the shelf 16 folded up to position 15 where it is against the upper part of the upright 10, whereupon the spring 17 will project through the recess 18. The latch 19 may be used for securing the shelf in its upright position. The 20 entire device may be then set out of the way until it is needed again.

It may be understood that the motor can be set on the portions 12 and 13 and both the motor and the vibrator bolted or screwed to a table or bench or support. Then when the vibrator is not needed 25 and it is desired to use the motor for other purposes, the shelf may be raised and held in upright position by means of the latch 19, and thereupon the motor can be used for other purposes.

The disc 23 can be removed and other implements, such as buffers, grinding stones, polishing wheels and so on may be substituted. In this 30 way the vibrator and motor can be fastened per-

manently to the laboratory bench and yet the vibrator will not interfere for using the motor for any purposes other than vibrating, for which it may normally be employed in a dentist's office.

Changes may be made in the material used and 5 in the shape, construction and arrangement of the parts of my improved vibrator, and it is my intention to cover by my claim, the use of any materials suitable for the purpose and any modifications in form, structure or arrangement of 10 the parts which may be reasonably included within the scope of such claim and within the scope of my invention.

I claim as my invention:

In a vibrator for dental use, a single piece unitary stand or support having an upright member and oppositely extending base members, said base members being adapted to rest on a table or the like and one of them being adapted to receive a motor placed thereon, the upright member having a recess to receive the motor shaft or a tool thereon, a shelf hinged to the upright member above the recess to swing from substantially horizontal position to upright position adjacent the upright member above the recess, a coil spring connected at one end to the shelf and at the other end to the upright member above said recess, said upright member having an opening to receive the spring when the shelf is swung toward its upper 25 position.

JOHN E. SHULTZ.
